DESIGN FOR AN ICE-CREAM CUP

Albert Aba Heyman, Baltimore, Md., assignor to
Maryland Baking Company, Inc., Baltimore,
Md., a corporation of Maryland

Application March 9, 1948, Serial No. 145,010

Term of patent 14 years

(Cl. D8—2)

To all whom it may concern:

Be it known that I, Albert Aba Heyman, a citizen of the United States, residing at Baltimore, in the State of Maryland, have invented a new, original, and ornamental Design for Ice-Cream Cups, of which the following is a specification, reference being had to the accompanying drawing, forming part thereof.

Fig. 1 is a top plan view of the ice-cream cup, embodying my new design.

Fig. 2 is a vertical section of the same on the line 2—2 of Fig. 1.

Fig. 3 is a bottom plan of the same.

Fig. 4 is a side elevation of the same.

I claim:

The ornamental design for an ice-cream cup, substantially as shown.

ALBERT ABA HEYMAN.
